UNITED STATES PATENT OFFICE.

DANIEL LONG, OF BROOKVILLE, PENNSYLVANIA.

PIANO-TUNING APPARATUS.

SPECIFICATION forming part of Letters Patent No. 745,634, dated December 1, 1903.

Application filed March 27, 1901. Serial No. 53,141. (No model.)

To all whom it may concern:

Be it known that I, DANIEL LONG, a citizen of the United States, residing at Brookville, in the county of Jefferson and State of Pennsylvania, have invented certain new and useful Improvements in Piano-Tuning Apparatus; and I do hereby declare the following to be a full, clear, and exact description of the same.

10 My invention relates to piano-tuning apparatus, and has for its object to provide a pin set in a metallic wrest-plate in such manner that it will be held in position by friction alone.

15 Reference is had to the accompanying drawings, in which—

Figure 1 represents a section of a wrest-plate, showing apertures to receive tuning-pins. Figs. 2, 3, and 5 represent modified 20 forms of tuning-pins. Fig. 4 represents a bolt adapted to sustain the form of pin shown in Fig. 3. Figs. 6 and 7 are two forms of bushings used to sustain the form of pin shown in Fig. 5. Fig. 8 is a transverse sectional view 25 of bar and pin.

The wrest-plate is made of metal, and it may be placed upon the ordinary frame-bar. It is preferably an inch and a quarter in thickness, but may have an additional plate, either 30 integral with it or secured to it in any well-known manner, as shown in Fig. 1 at a' , the purpose of which will appear later.

The apertures a in the wrest-plate A, I prefer to make fifty hundredths of an inch 35 in diameter at the top and forty-four hundredths of an inch at the bottom, and the aperture is made perfectly smooth by emery-grinding. The body or bearing surface of the tuning-pin in like manner is ground perfectly smooth and is made of corresponding 40 dimensions, so as to accurately fit the aperture of the wrest-plate. It is found that pins of the size and being tapered in the degree described will retain their hold in the wrest-plate better than those of any other size and 45 shape.

In position I prefer to have the body or bearing portion of the pin to extend a little above the wrest-plate to aid in preventing 50 moisture or dust from entering the joint and to allow for the adjustment of the pin. The neck b of the pin is smaller, and it has at its

top an oblique aperture to receive the string when it is wound upon the pin. b' is the head of the pin, constructed in the usual manner, to which the tools may be applied in adjusting said pin. 55

Fig. 3 shows a modification in which the pin is provided centrally with a longitudinal aperture d and at the lower end with a rectangular slot d' . The bolt shown in Fig. 4 is adapted to enter the aperture d , the web e of said bolt registering with the slot d' . As the head of the bolt bears against the bottom of the wrest-plate, turning down the nut secures 65 the pin firmly in the plate and holds it in position after it has been set by the operator. This pin must be made short enough to provide for its adjustment. It is also necessary to provide space for the head of the bolt. A 70 shoulder c is formed at the top of the portion b , against which the instrument is placed in forcing the pin into position.

A further modification is shown in Fig. 5, in which a shoulder is formed at the base of the 75 neck portion b , against which the bushing (shown in Fig. 6 or Fig. 7) operates to hold the pin in the wrest-plate. The bushing is provided with an external screw-thread, which engages a corresponding screw-thread formed 80 in the plate a' .

Pins constructed as above described move regularly in their sockets and the tuning is accomplished without jerking the pins, which so frequently breaks the strings. 85

Having described my invention, what I claim as new, and desire to secure by Letters Patent, is—

1. In a piano-tuning apparatus, a wrest-plate provided with apertures contracted 90 from the face thereof and pins adapted to fit snugly in said apertures, the shank of the pins extending above the face of said plate; and means for applying pressure to the pins, having one bearing thereon above their greatest 95 diameter and another bearing on the wrest-plate, whereby said pins are sustained in their sockets, substantially as specified.

2. A piano-tuning pin, having a tapered bearing portion and means for holding it in 100 place comprising a central longitudinal aperture and a bolt registering in said aperture, the head of the bolt bearing against the bottom of the wrest-plate and the nut operating

against the head of the pin, said pin being provided above the body portion with a shoulder whereby it may be adjusted, substantially as specified.

3. A tuning-pin for pianos and the like, having a central longitudinal aperture and a rectangular slot in its end, and a bolt operating in said aperture which is provided with a web registering in said slot for sustaining the pin in position, substantially as specified.

4. In a piano-tuning apparatus, a wrest-plate provided with apertures contracted from the face thereof, and pins adapted to

snugly fit in said apertures, the shank of the pins extending above the face of said plate; 15 and a screw-threaded member, having a bearing on said pins above their greatest diameter and a reciprocal bearing on said wrest-plate, whereby pressure is applied to the pins to sustain them in their sockets, substantially 20 as specified.
